UNITED STATES PATENT OFFICE.

JAMES D. NELSON, OF CINCINNATI, OHIO.

ELECTRIC-ALARM TRANSMITTER.

1,427,543.

Specification of Letters Patent. Patented Aug. 29, 1922.

Application filed June 4, 1917. Serial No. 172,565.

To all whom it may concern:

Be it known that I, JAMES D. NELSON, a citizen of the United States of America, and resident of Cincinnati, in the county of 5 Hamilton and State of Ohio, have invented a new and useful Improvement in Electric-Alarm Transmitters, of which the following is a specification.

An object of my invention is to produce 10 a mechanically tripped electric alarm transmitter for supervising the valves, pressure, temperature, water level or other apparatus or conditions existing within automatic fire extinguisher systems, and which is connected directly with the desired portion of 15 the system to be supervised.

Figure 1 is a side elevation of my improved transmitter, mounted in a casing secured to the side of an element of a sprinkler system to be observed, certain portions 20 of the transmitter being broken away for convenience of illustration.

Figure 2 is an elevational view of the reverse side of my improved transmitter, 25 showing diagrammatically an electric signal system connected therewith, certain parts of the transmitter being shown broken away for convenience of illustration.

Figure 3 is an end view of my improved 30 transformer taken on the line 3—3 of Figure 2.

In the drawings I have shown my improved transmitter directly connected with a tank for indicating variations of pressure 35 existing therein, a pressure responsive diaphragm 6 being mounted upon and communicating with the interior of the tank for tripping the transmitter. A weighted lever 7 operatively connects the diaphragm with 40 the transmitter and controls it in a manner to be hereinafter explained.

The main portion of my improved transmitter consists of a gear train comprising gear wheels 8 and 9 with pinions 10^a and 11^a 45 for completing the train, gear 9 and pinion 10 being secured to a shaft 11. Gear 8 is secured to a winding shaft 12 and pinion 11^a is mounted upon another shaft 13, shafts 11, 12 and 13 being journaled in plates 14 and 50 15 which are spaced apart by means of the usual spacing posts 16 commonly employed in clock work mechanisms. In addition to shafts 11, 12 and 13 another shaft 17 is provided, which has mounted upon it a pawl 18 55 which cooperates with a ratchet 19 in controlling the speed of the train in response to

the action of the spring. In addition to gear 9 and pinion 10^a shaft 11 has mounted upon one end a cam 20 which cooperates with a pin 21 on a trigger 22 which is pivotally mounted at a point 23 on plate 15 of the transmitter. On the opposite end of shaft 11 a signal wheel 24 is mounted, the teeth of which are adapted to cooperate with a signal-sending circuit breaker 25 consisting of a contact 25^a and an arm 25^b which is operated upon by the teeth of the signal wheel to make and break the circuit. Trigger 22 is provided at one end with a pin 26 which cooperates with the free end of a 70 tripping lever 27 which is pivotally mounted at its opposite end upon a pivot pin 28 provided in a lug 29 extending from plate 15. Tripping lever 27 is provided with a pin 30 which cooperates with a finger 31 75 extending from pawl 18 so as to release or stop the vibrating motion of the pawl as desired. At the end of trigger 22 opposite to that which is provided with pin 26, a pin 32 is mounted, this pin bearing against 80 the periphery of a notched disc 33 which is pivotally mounted at a point 34 on plate 15 of the transmitter. One notch 35 of disc 33 is adapted to be engaged by a pin 36 carried by lever 7 which extends from diaphragm 85 6, the remaining notches 37 and 38 being provided for engagement therewith of pin 32 of trigger 22. In order to cause trigger 22 to move in a direction such as to bring its pin 32 into engagement with either of 90 the notches 37 or 38, I have provided an arm 39 upon which a weight 40 is adjustably mounted for the purpose of causing the trigger to swing and cause its pin 26 to knock tripping lever 27 out of locking engagement with the transmitter mechanism 95 so that pin 30 thereof will release finger 31 and permit vibration of pawl 18 and consequent operation of the transmitter. To cause tripping lever 27 to be moved to bring 100 its pin 30 into engagement with finger 31 to stop the operation of the transmitter, I have provided an arm 41 upon which a weight 42 is adjustably mounted. In addition to gear 8 there is mounted upon shaft 12 a notched disc 43 which is provided with notches 44 and 44^a for the reception of a pin 45 located in lever 27 so that when pin 45 engages notch 44 the lever will be permitted to move into position to bring its pin 110 30 into engagement with finger 31 of pawl 18. It is between gear 8 and disc 43 that I

have preferably mounted the spring, not shown, which controls my improved transmitter. In addition to gear 8 and disc 43 I have also mounted a disc 46 upon shaft 12, this disc being provided with diametrically opposed notches 47 and 48 which are provided for engagement with a pin 49 upon an arm 50 which is pivotally mounted at a point 51 upon plate 14 of the transmitter, 5 arm 50 being provided at its opposite end with a pivotally mounted pawl 52 which has a lug 53 carrying a pin 54 adapted normally to engage an inclined surface 55 of plate 14 of the transmitter, the free end 56 of pawl 10 52 being hooked for cooperation with pins 57 and 57^a mounted upon gear 8 at diametrically opposite points. A spring 58 which is secured to arm 50 and which bears at its opposite end against pawl 52, is provided 15 for holding pin 54 normally in engagement with inclined surface 55 in position for the hook 56 to be engaged by pin 57 of gear 8. Upon the inner face of disc 46 is provided a cam 59, which is shown in dotted lines in 20 Figure 2, this cam being provided with ends inclined in the same direction for the purpose of engaging pin 54 and lifting pawl 52 out of engagement with pin 57 during certain portions of the operation of the 25 transmitter. Gear 8 and pinion 10^a bear a ratio of 6 to 1 with relation to each other so that six revolutions of signal wheel 24 will be obtained for each revolution of discs 43 and 46. During certain portions of the 30 operation of the transmitter, arm 50 is brought to a position in which pin 49 at one end thereof is brought out of one of the notches 47 or 48 and for the purpose of holding the arm against further movement after 35 pin 49 has been brought out of the notch in which it is located, I have provided a pin 60 mounted upon plate 14 of the transmitter frame.

For the purpose of illustrating the operation of my improved transmitter I have 40 shown it in Figure 2 as being connected with a normally closed circuit system 61 which controls a local or central station system 62 and in the description of the operation I 45 will merely refer generally to these closed and open circuit systems, since their operation is well known. Under normal conditions, diaphragm 6, which is under the influence of the pressure existing within the 50 pressure tank with which it is shown connected, retains lever 7 in position to hold disc 33 in the position disclosed in Figure 1. In this position notches 37 and 38 of the disc are located distances equally spaced from 55 pin 32 of trigger 22. In this position of the trigger its pin 21 is held out of engagement with cam 20 and its pin 26 is held out of engagement with the lower end of lever 27. 60 Also in this normal condition of the transmitter, disc 43 is retained in such a position

that its notch 44 permits the engagement therewith of pin 45, thus allowing lever 27 to bring pin 30 into engagement with finger 31 to retain pawl 18 against vibration. The transmitter mechanism when in this condition has cam 20 located in the full line position disclosed in Figure 1 and signal wheel 24 is in the full line position disclosed in Figure 2. It will also be seen that pawl 52 has its pin 54 in engagement with inclined 70 surface 55 and it will also be seen that the hooked end 56 of pawl 52 is free from either of the pins 57 or 57^a. Because of the action of spring 58 arm 50 is held in a position with its pin 49 in engagement with notch 48. 80

It will be assumed that the transmitter has been completely wound by placing a key upon the square end of shaft 12 to rotate it in the direction indicated by the arrow in Figure 2, thus causing the parts to be under 85 the influence of the propelling spring. It will be assumed that either an increase or a decrease in pressure from the normal pressure existing within the pressure tank, has occurred. This will cause diaphragm 6 to either expand or collapse and thus cause lever 7 to rotate disc 33 to bring either of the notches 37 or 38 into position to be engaged by pin 32. Trigger 22 upon engagement with either of these notches, will then 90 swing to bring its pin 26 into engagement with the lower end of tripping lever 27 and cause lever 27 to move to a position to bring its pins 45 and 30 respectively out of engagement with notch 44 of disc 43 and finger 31 of pawl 18. The transmitter having been released the signal wheel 24 moves in the direction of the arrow in Figure 2, to bring its teeth successively beneath switch arm 25^b and thus cause the transmission of a signal 95 to central station represented by circuit 62. During the transmission of this signal, pin 57^a is being brought closer and closer to hook 56 of pawl 52. The action of the engagement of pin 57^a with hook 56 is to cause 100 pawl 52 to pull upon arm 50 and thus withdraw pin 49 from engagement with notch 48 of disc 46. The transmitter is then brought to a stop by pin 57^a causing pawl 52 to pull arm 50 into engagement with pin 60 which 105 forms an abutment to prevent further operation of the transmitter.

Having constructed my transmitter with gear 8 and pinion 10^a bearing a ratio of 6 to 1 with relation to one another, the distance 110 which pin 57^a has to travel before it engages hook 56 and brings arm 50 into engagement with abutment 60, is nearly $\frac{1}{3}$ of a revolution of gear 8 thus causing signal wheel 24 to rotate nearly two revolutions and, to 115 bring all of its teeth twice under switch arm 25^b to transmit the signal. This indicates trouble or a change from the normal conditions existing within the system. In the 120 illustrated embodiment of my invention such 125 130

a signal would indicate either a rise above or a drop below the normal pressure existing within the pressure tank. The signal wheel 24 having transmitted the signal twice, it is stopped a short distance from completing two revolutions so that the last signal tooth 24^a will be brought to a stop just after having passed beneath switch arm 25^b so that the transmitter is locked against further movement with tooth 24^a in the dotted line position disclosed at 24^b in Figure 2. Cam 20 being mounted upon shaft 11 with signal wheel 24, the point of cam 20 is brought beneath pin 21 and stopped in the dotted line position 20^a as disclosed in Figure 1. The trigger 22 being thus held from engagement with either of the notches 37 and 38, the diaphragm 6 is free to vibrate lever 7 and disc 33 in response to subsequent changes in the pressure of the system before the transmitter is again placed in normal condition by rewinding it. The transmitter, after normal conditions have been restored in the system which is under supervision, is rewound by placing a key upon the squared end of shaft 12 and rotating the shaft in the direction of the arrow in Figure 2, notch 43 being brought to the position occupied by notch 47 in this rewinding operation. This rotates cam 59 with disc 46 and brings one inclined face 59^a thereof beneath pin 54 of pawl 52 and lifts the pawl from engagement with pin 57^a. Pawl 52 being disengaged the action of its spring 58 is to cause arm 50 to resume its former position with pin 49 in engagement with notch 47 or 48 as the case may be, thereby preventing overwinding which would result in consequent rushing or crowding effect on the mechanism and in turn if persisted in would have a bad effect upon the signal from signal wheel 24. Tripping lever 27 having been held from engagement with finger 31 of pawl 18 by having its pin 45 in engagement with the periphery of cam 43, at the end of the trouble signal operation of the transmitter, the transmitter is free to operate immediately upon disengagement of pawl 52 from pin 57^a in response to the action of end 59^a of cam 59 during the rewinding movement.

The transmitter having been rewound and the pawl 52 having been released, the transmitter starts to operate. The operation is continued until pin 57 is brought to the position occupied by pin 57^a in Figure 2, as the notch 44 of disc 43, has been previously rotated through $\frac{1}{3}$ of a rotation of cam 43, and complementary notch 44^a rotated through the same distance now upon completion of the winding movement of the transmitter, whereby the transmitter may operate to complete the revolution of the disc 43 to bring the notch from the position 44^b to the position occupied by notch 44 as disclosed in Figure 2. This last mentioned operation of

the transmitter causes the transmission of an O K signal, signal wheel 24 being rotated once to transmit an O K signal to central station 62. Since the trouble signal rotation of signal wheel 24 brought tooth 24^a to the position 24^b disclosed in dotted lines in Figure 2, the rotation of signal wheel 24 for an O K signal will be accompanied by a slightly greater rotation than one revolution of said signal wheel 24, so that tooth 24^a will be brought back to the position disclosed in full lines in Figure 2. This results in cam 20, which was stopped in the dotted line position shown in Figure 1 upon completion of the trouble signal, being brought to the full line position disclosed in Figure 1 so that pin 21 of trigger 22 will be freed to permit pin 32 of the trigger 22 to ride on the face or periphery of cam 33, and to again enter either one of the notches 37 or 38 upon any subsequent disturbance in the normal conditions of the system. Notch 44^a at the completion of this O K signal operation of the transmitter, will have been brought to the position formerly occupied by notch 44 in Figure 2, this, of course, is after it had been brought to the dotted line position disclosed at 44^b in Figure 2, through the trouble signal operation. Thus upon completion of the O K signal, lever 27 is permitted to drop into engagement with finger 31 so that pin 30 will prevent further operation of the transmitter. The transmitter is thus placed in condition for again transmitting a trouble signal when the conditions in the pressure tank, herein employed for illustration are other than normal. It can easily be seen that the transmitter cannot be positioned at normal, that is, with pin 45 cooperating with either notch 44 or 44^a of cam 43, for the following reasons. Suppose the transmission of the aforesaid trouble signal due to a fall in the pressure in tank, has occurred and the transmitter has come to rest in the manner described. Now without restoring the pressure conditions, the transmitter is rewound and conditioned for signal operation. When cam 20 disengages pin 21 pin 32 of trigger 22 will fall into notch 38, said notch being positioned as indicated at 38^a. The pin 26 of trigger 22 will engage locking arm 27 so as to prevent its pin 45 entering either of the notches 44 or 44^a of cam 43, hence, the O K signal will be sent to central station 62 and the supervised apparatus being in trouble and the transmitter thereby conditioned for two operations more, or a total of three signals will be sent to central station 62 before said transmitter is again locked, it is therefore impossible for the central office to be mistaken through signals regarding the condition of the supervised device or apparatus, for there are three distinct signals, one of which indicates trouble, a second indicates a

continuation of the trouble, and a third signal indicating that the transmitter has been properly rewound and that the condition in the supervised apparatus has been reconditioned to normal.

It will be seen that I have provided means for preventing the winding of the transmitter at times other than the proper time for its rewinding. It will also be seen that 10 overwinding of the propelling spring is prevented since the disengagement of pawl 52 from either of the pins 57 or 57', immediately permits pin 49 to again engage either of the notches 47 or 48 and thus stop further 15 winding of the transmitter after it has been wound sufficiently.

Although I have illustrated my transmitter as applied to the supervision of a pressure tank, it may as readily be applied to 20 other portions of a system to be supervised, without changing any of the principal features of novelty of my improved construction.

Having thus described my invention, what 25 I claim is:

1. An electric signal transmitter consisting of a signal sending mechanism, a transmitter tripping trigger operatively connected therewith, means responsive to variations 30 in conditions within a system to be supervised, adapted to release the trigger to trip the transmitter, and a second means adapted to return the trigger to and retain 35 it in its normal position to permit operation of the condition responsive means.

2. In combination with an object to be supervised, an electric signaling system comprising an element responsive to changes in a system to be supervised, a signal transmitter 40 comprising a windable spring mechanism and controlled by the responsive means for signal operation in response to variations of conditions within the system supervised, and means for causing the transmitter 45 to send a different signal upon rewinding.

3. In combination with an apparatus to be

observed, an electric signaling system comprising means responsive to variations in the apparatus, a signal transmitter operated by a windable spring mechanism, and means controlled by the responsive means for conditioning the transmitter to give a signal in response to variations of conditions in the apparatus, and means for conditioning 55 the transmitter for another signal upon restoration of the conditions in the apparatus observed and upon the rewinding of the transmitter.

4. An electric signal transmitter consisting of a member responsive to variations in conditions within a system to be supervised, a trigger responsive to operation of said condition-responsive member, a tripping lever adapted to be operated in response to 60 operation of the trigger, a mechanism adapted to operate in response to tripping of the tripping lever to transmit a trouble signal upon changes from normal conditions within the system, and to transmit an O K 65 signal upon restoration of the system and transmitter to normal conditions.

5. An electric signal transmitter comprising a power-propelled signal transmitting mechanism operated by a windable spring 70 mechanism, means responsive to variations in conditions within a system to be supervised, adapted to trip the transmitter to transmit a trouble signal, and a second means adapted to lock the transmitter 75 against predetermined winding of the spring thereof upon restoration of the system and transmitter to normal conditions, said mechanism being adapted to render inoperative the second mentioned means in response to changes from normal conditions 80 in the system.

In testimony whereof, I have hereunto subscribed my name this 31st day of May, 1917.
